UNITED STATES PATENT OFFICE.

FREDERIC P. GATES, OF WEST HARTFORD, CONNECTICUT, ASSIGNOR TO THE FULLER-GATES COMPANY, OF HARTFORD, CONNECTICUT, A CORPORATION OF CONNECTICUT.

KNOB FOR SNAP SWITCHES.

Application filed January 16, 1924. Serial No. 686,644.

To all whom it may concern:

Be it known that I, FREDERIC P. GATES, a citizen of the United States, and a resident of West Hartford, in the county of Hartford and State of Connecticut, have invented new and Improved Knobs for Snap Switches, of which the following is a specification.

My invention relates more especially to 10 that construction of a knob whereby it is operatively connected with the actuating mechanism of a snap switch, and an object of my invention, among others, is the production of a knob having simple and efficient means for accomplishing such result.

One form of device embodying my invention and in the construction and use of which the objects herein set out, as well as others, may be attained, is illustrated in the 20 accompanying drawings, in which—

Figure 1 is a view in section through my improved knob on a plane denoted by the dotted line 1—1 of Figure 4.

Figure 2 is a similar view on a plane denoted by the dotted line 2—2 of Figure 4.

Figure 3 is a bottom view of my improved knob with the bottom plate removed and with parts broken away to show construction.

Figure 4 is a bottom view of the knob with the bottom and attaching plates removed and with parts broken away to show construction.

Figure 5 is a view in elevation of the knob with the bottom plate removed and with parts broken away to show the manner of securing the attaching plate.

Figure 6 is a detail perspective view of the attaching plate.

The invention herein set forth provides a switch knob having special means for securing thereto bottom and attaching plates employed to affix and connect the knob to the mechanism of a snap switch, in the drawings herein the numeral 8 indicating a knob that may be of any desired shape and material and having the usual indicating point 9 adapted to register with indicating words or characters to denote the positions of the

conducting elements of the switch. This knob has a hole extending inwardly from its under surface, the inner portion 10 of this hole being preferably of non-circular shape, and the outer portion 11 of the hole being preferably round. Grooves 12 are formed

on diametrically opposite sides of this hole, extending lengthwise thereof, and locking recesses 13 are formed at the inner ends of the grooves, the locking recesses being of a width greater than the width of said groove. 60

An attaching plate 14 is provided with arms 15 adapted to be located in the grooves 12, said arms terminating in locking fingers 16 adapted to enter the locking recesses 13. The attaching plate is provided with a central opening and also with an aperture 17 to receive the spring tensioning finger common to the mechanism of a snap switch, and in a manner that will be readily understood. 70

Fastening clips 18 project from the attaching plate into openings 19 in a bottom plate 20, there being preferably two of said clips arranged on diametrically opposite sides of the opening in the plate. This bottom plate is preferably composed of fiber of any suitable kind and the clips are bent over, as shown in Figure 1, to secure the bottom and attaching plates together, and an aperture is formed in the bottom plate to register with the aperture in the attaching plate, the spring tensioning finger of the switch mechanism projecting through both of said apertures in a manner that will be readily understood. 75

A spring supporting plate 22 is located in the outer portion 11 of the hole in the knob, this plate having projections 23 extending into the grooves 12, and a spring 24 is seated on said plate, the inner end of said spring 90 thrusting against the head 25 of a connection 26 for securing the knob 8 to the spindle 27 of the switch mechanism. This connection projects through the bottom and attaching plates and has a bearing fit in a hole in the center of the bottom plate, a threaded hole 28 is made in the connection to fit the screw threaded end of the spindle 27, and the head 25 is of non-circular shape corresponding to the non-circular shape of the inner portion 10 of the hole in the knob, so that the knob may be moved outwardly independently of the connection 26 and against the tension of the spring 24. 95

In assembling the parts the connection 26 with the spring 24 therein is inserted in the hole in the knob, the plate 22 is placed in position, as shown in Figures 1, 2 and 5 of the drawings, and the attaching plate 14 with the arms 15 thereon in the position shown in 105 110

Figures 1, 5 and 6 of the drawings is located with said arms opposite the grooves 12, which arms are then bent, as by the use of a suitable tool, into said groove, and as shown 5 in Figures 1 and 2 of the drawings. The parts are thus secured in place and the bottom plate may then be secured by the clips 18, or such bottom plate may be thus secured before the attaching plate is engaged with 10 the knob.

To secure the knob to the spindle 27 the connection 26 is engaged with the screw threaded end of said spindle, in which position the end of the spring tensioning finger 15 of the switch mechanism will be spaced a slight distance from the under side of the bottom plate. As the knob is turned to further engage the connection with the screw threaded end of the spindle, the end of said 20 spring tensioning finger will eventually be pressed against the bottom plate, and in order to permit the connection to be screwed down the end of the spring tensioning finger is prevented from entering its aperture in 25 the attaching and bottom plates by pulling the knob outwardly on the connection 26 and against the tension of the spring 24, until said connection has been engaged sufficiently with the threaded end of the spindle, after 30 which the spring tensioning finger will be permitted to engage within its apertures in the attaching and bottom plates and also in the knob, and force upon the knob being released the spring 24 will press the knob to 35 its seat on the head 25 and cause the spring tensioning finger to enter said apertures. To remove the knob from the spindle the former is pulled outwardly against the tension of the spring until the spring tensioning finger 40 is removed from its apertures and the knob is then turned to unscrew it from the spindle, the pull upon the knob being retained to prevent the spring tensioning finger from entering its apertures during this unscrewing 45 operation.

This operation of securing the knob in place and of removing it is not new, the invention residing in novel construction and arrangement of the parts that, while different from prior devices, yet permits this old 50 operation of attaching and removing the knob.

In accordance with the provisions of the 55 patent statutes I have described the principles of operation of my invention, together with the device which I now consider to represent the best embodiment thereof; but I desire to have it understood that the device shown is only illustrative, and that the invention may be carried out by other means 60 and applied to uses other than those above set out.

I claim:

65 1. A switch knob having a hole therein, means within said hole for attaching the 120 under surface of the knob, means for secur-

70 knob to a switch spindle, two plates of different material on the under surface of the knob, means for securing said plates to the knob, and means for securing said plates together.

2. A switch knob having a hole therein with a locking recess in the wall of said hole, means for attaching said knob to a switch spindle, and a plate located on the under side of said knob and surrounding the lower end of the opening and having an arm with a locking finger thereon located in said recess to secure said plate to the knob. 75

3. A switch knob having a hole therein with a groove in the wall of said hole and a locking recess opening into said groove, means for attaching said knob to a switch spindle and a plate located on the under side and exteriorly of said knob and having an arm to be located in said groove and a locking finger to be located in said recess to secure said plate to the knob. 80 85

4. A switch knob having a hole therein with a locking recess in the wall of said hole, means for attaching said knob to a switch spindle, and a plate located on the under side and exteriorly of said knob and having a bendable arm with a locking finger thereon whereby said arm may be bent to locate said finger in said locking recess to secure 90 95 said plate to the knob.

5. A switch knob having a hole therein with a locking recess in the wall of said hole, means for attaching said knob to a switch spindle, plates located underneath 100 said knob, and means for securing said plates together, one of said plates having an arm bordering a central opening with a locking finger thereon located in said recess to secure said plates to the knob. 105

6. A switch knob having a hole therein with a locking recess in the wall of said hole, means for attaching said knob to a switch spindle, plates located underneath 110 said knob, means for securing said plates together, there being a central opening in the inner plate and an arm projecting from the wall of the inner plate opening and having a locking finger located in said recess to secure said plates to the knob. 115

7. A switch knob having a hole therein with a groove in the wall of said hole and a locking recess opening into said groove, means for attaching said knob to a switch spindle, plates located underneath said knob, interlocking connections for securing said plates together, and an arm projecting from the inner plate to be located in said groove, said arm having a locking finger to be located in said recess to secure said plates to 125 the knob.

8. A switch knob having a hole therein, means within said hole for attaching the knob to a switch spindle, two plates on the under surface of the knob, means for secur- 120 125

ing said plates to the knob, and a clip on one of said plates projecting through an opening in the other plate to secure said plates together.

- 5 9. A switch knob having a hole therein, means within said hole for attaching the knob to a switch spindle, two plates on the under surface of the knob, a clip on the inner plate projecting through an opening in 15
10 the outer plate to secure said plates together, and means for securing said plates to said knob.

10. A switch knob having a hole therein

with a locking recess in the wall of said hole, means for attaching said knob to a switch spindle, two plates located underneath said knob, one of which plates is an attaching plate, an arm projecting from said attaching plate and having a locking finger to be located in said locking recess to secure 20 said plate to said knob, and a clip projecting from said attaching plate through an opening in the other plate to secure said plates together.

FREDERIC P. GATES.
